ABSTRACT OF THE DISCLOSURE

A transistor comprises a body of the semiconductive material with a plurality of protrusions integrally provided on a top face of said body, said body partitioned into more than one base region, more than one emitter region and a collector region, said base and emitter regions extended along at least external surfaces of said protrusions which are respectively flattened at its top contact face.

A force applicator has a relatively larger flattened face which rests on said top contact faces for applying a mechanical force to said transistor, said transistor converting the transmitted load into current intensity.

Background of the invention

The present invention relates to semiconductive electromechanical transducers, and more particularly to a semiconductive transducer adapted for converting an alternate load such as a stylus driving force that is transmitted through a force applicator to a transistor into current intensity.

A well known semiconductive transducer comprises a planar type transistor comprising a body of semiconductive material which is partitioned into a base, an emitter and a collector region by diffusing suitable impurities on a face of said body, and a needle like force applicator made of such a hard material as sapphire, diamond crystal and which has a tip contact area of the order of 10 microns in curvature radius, said tip contact area resting on the flat face of the semiconductive body for applying a mechanical load on the emitter region of the transistor.

A first problem of those transducers is how to improve the sensitivity of the transducer depending upon variate of the current intensity. As the increase of the mechanical load per unit area on the emitter region causes the magnitude of collector current to be decreased in such transducers for converting the force such as stylus driving force into current intensity, it is desirable that the top contact area is small as far as possible to enlarge the range of variate of current. An estimated maximum load in practice is predestined preferably near but less than the value of the elastic limit of semiconductive material so that the load applied on the emitter region is frequently charged, particularly in the case where said applied load is an alternate load, in excess of the elastic limit defined by the fatigue limit of the semiconductive material in spite of the fact that the applied load is desirably limited within the elastic limit. Finishing condition of the surface of the transistor body further causes the transmitted force to be concentrated locally on said surface. As a result damages such as cracks or deformations of the contact surface of the transistor are caused by the locally overcharged force.

It is possible to avoid such damages by utilizing a needle like force applicator made of such as tungsten,

2

iron or the like being softer than diamond or sapphire, but impossible to avoid degrading the sensitivity of the transducer as the tip of the needle is deformed by a comparatively lower load which produces an internal stress in the transistor within the fatigue and locally allowable limit.

The nearer the loaded area on the emitter region is presented to an emitter junction exposed on the top face of the transistor body, the larger the variate of current with respect to a certain load applied on the emitter region is increased. However, as the contact area of the needle is small, to register the contact area of the needle on the exposed emitter junction is difficult and as the latter is relatively weak with respect to the mechanical load, it is undesirable to load the load thereon.

It is necessary to keep the good sensitivity of the semiconductive transducer and reduce the transmitted load per unit area on the emitter region.

A semiconductive transducer for deleting these defects is described in a copending application Ser. No. 602,303 filed Dec. 16, 1966, and assigned to the same assignee as the present invention. The transducer as described comprises a transistor which comprises a body of the semiconductive material with a protrusion integrally provided on a top face of said body, said body partitioned into a base region, an emitter region and a collector region, said base and emitter regions extended along at least external surface of said protrusion which is flattened at its top contact face, and a force applicator having a large flat contact face for face-to-face contact with the contact face of the protrusion.

The exposed emitter junction is positioned out of the contact face so that when loading a mechanical force or alternate force on the emitter region at the contact face the exposed emitter junction is kept free from destruction due to the mechanical load imposed. Although the dimension of the contact area of the applicator is the same as that of the contact face of the protrusion and larger than that of the prior needle like applicators, an average reduction ratio of current with respect to the applied load per unit area on the emitter region is maintained at a level higher than that of the prior art transistor, because of the fact that the nearer to the edge of the contact face or its neighborhood, the greater the variate of the current becomes.

Summary of the invention

An object of this invention is to provide a semiconductive transducer comprising a transistor which comprises a body of semiconductive material and a plurality of protrusions integrally provided on a top face of the body and spaced one from the other, and a force applicator having a flat contact face which contacts with the contact faces of said protrusions in face-to-face relationship, whereby the reduction ratio of current can be maintained with the contact faces of the protrusions.

It has been found that, when the overall contact area between a force applicator and a plurality of protrusions equal to the contact area between an applicator and a single protrusion as described in a copending application Ser. No. 602,303, an average reduction ratio of the current in a transistor having such a plurality of protrusions can be kept at a level higher than that in a transistor having a single protrusion. This means that if the same reduction rate is kept, the former is more advantageous than the latter for keeping further safely the emitter region against the applied load. Additionally, the applicator is stably rested on the protrusions and easiness of loading a force against the applicator under stable condition is improved because situations of the protrusions are spaced one from the other.

Description of the drawings

FIG. 1 is an observation graph for variate of collector current which is produced in a transistor concerning to the invention;

FIG. 2 is an elevational view illustrating one embodiment of the semiconductive transducer according to the invention;

FIG. 3 is a plan view illustrating the embodiment shown in FIG. 2;

FIG. 4 is a sectional view illustrating the embodiment shown in FIG. 2, a force applicator being shown as chain line therein;

FIG. 5 is a sectional view illustrating another embodiment of the semiconductive transducer, partly broken away, according to the invention;

FIG. 6 is a sectional view illustrating a further embodiment of the semiconductive transducer according to the invention; and

FIG. 7 is an indication graph for variate of current with respect to an amount of the applied force on the emitter region.

Detailed of the description

Referring to FIGS. 2 to 4, a semiconductive transducer according to this invention includes a force applicator 24 shaped into a circular cylinder and made of such material as sapphire, tungsten, iron or the like, and a transistor comprising a body 15 of semiconductive material with three protrusions 12, 13, 14 integrally provided on the face of said body 15 and spaced one from the other. Said protrusions have flat top contact faces 12a, 13a, 14a for carrying the applicator. The transistor has a base region 17 extended in the body 15 along an area on a top face including external surfaces of the protrusions, three emitter regions 18, 19, 20 respectively extended in at least the protrusions along its external surfaces, and a collector region indicated at 16 by diffusing suitable impurities from side of the top face of the body.

Portions of emitter junctions 18a, 19a, 20a exposed on a surface of the body 15 are respectively presented at the base of the protrusions with respect to each of the emitter regions or may be at the periphery surface of the protrusions except of the top contact faces.

Except of the external surfaces of the protrusion, there is an insulating film 23 on the face of the body 15. Mounted on the semiconductive body 15 through the insulating film is a base electrode 22 which is connected to the base region at one end, and mounted on the bottom surface of the body 15 is a collector electrode 21. When the applicator cylinder 24 is made of such conductive material as iron, it may be utilized as an emitter electrode.

The applicator 24 of which under surface is flattened and extended at large is completely attached and carried on all top surfaces of the protrusions so that the transmitted force, for example, such alternate load as stylus driving force is sufficiently and positively applied to the emitter regions.

As shown in FIG. 1, variate of current produced in a transistor under a test load is measured in respect of various plots on traverse from a medium portion to a periphery edge portion on the top surface of the protrusion. The condition of measurement is given for instance by that a diameter of the top contact face of the protrusion is about 10 microns, grounded emitter current gain is $hFE=30$, and the depth of the emitter diffusion is about one micron. In this case, a force applied on the applicator is 4 gr. It should be comprehended that the absolute variate of current is increased when a load is applied at the periphery edge.

In the arrangement, although the mechanical load per unit area applied to the emitter regions is decreased by the contact area extended larger than that of the prior needle like applicator, the reduction ratio of current as an average value is maintained at a high level so that the good sensitivity of the transducer is kept and simul-

taneously it is possible to avoid such damage as crack or deformation of the surface of the transistor.

As the emitter region contacted to the applicator is further separated into the three areas corresponding to numbers of the protrusions, rate of whole periphery edge areas of the protrusions against its whole medium areas are kept larger than those of the case wherein the emitter region depends on one protrusion so that if the same contact area is constant, the reduction ratio of the current is further increased or if the same reduction ratio of the current is kept, the maximum load per unit on the emitter is reduced because the contact area is extended.

As shown in FIG. 5, a force applicator 124 is coated with gold 124b on the surface of the body 124a for connecting it to a transistor 116 by alloying the gold to the transistor body made, for instance, of silicon at about 400° C., and particularly to improve conductivity between the force applicator and the emitter regions in the case where the force applicator is utilized as emitter electrode. As a result, it is possible to cause the best contact condition to be effected between the applicator and the top contact faces of the protrusions without the effect according to the finishing of the face. Alternatively, the applicator 124 may be connected to the transistor 116 by conducting bonding material.

Referring to FIG. 6, a transistor comprises a body with a stage 200 integrally provided on its face, and therewith three protrusions 212, 213 and 214 integrally provided on its face. Said body is partitioned into a base region 217 extended in a top face along an area including the external surface of the stage, three emitter regions 218, 219 and 220 extended in a top face along areas including at least the external surfaces of the protrusions, and a collector region which is remains. A base electrode is indicated 222 and a collector electrode is indicated at 221. A force applicator cylinder 224 rests on the protrusions.

In these embodiments, it is advantageous that said protrusions carrying the applicator are disposed on one face of the body away from each other for placing the applicator on the transistor as described in the meantime.

FIG. 7 indicates an observed finding of one embodiment according to the invention, wherein variate of current produced in transistor is varied in respect of transmitted force value (gr) against the transistor.

Although in the foregoing embodiments the transducer of this invention has been described and illustrated as having three protrusions, a plural number of such protrusions may be provided. In the embodiments, the number of the emitter regions is proportioned to that of the protrusions, but may be common to a plurality of the protrusions and the base region is common to a plurality of the emitter regions, but may be proportioned to the number of the emitter region.

Alloying the gold to the transistor body may be changed by alloying such metal that is melted at suitable low temperature limited not to invade character of the transistor.

While the invention has been described in connection with some embodiments it will be obvious to those skilled in the art that the invention is not limited to the preceding examples but various changes and modifications can be made in the details of structure without departing from the true spirit and scope of the invention.

What is claimed is:

1. A semiconductive electromechanical transducer comprising a transistor which comprises a body of the semiconductive material and a plurality of protrusions integrally provided on a top face of said body, said body partitioned into more than one base region, more than one emitter region and a collector region by diffusing suitable impurities on said face of the body, said base and emitter regions extended along at least external surfaces of said protrusions, said protrusions respectively flattened at its top contact face, and a force applicator having a large flat face which rest on said top contact faces for

face-to-face contact with the top contact faces of the protrusions.

2. A semiconductive electromechanical transducer according to claim 1 in which the applicator is made of conductive material and serves as an emitter electrode.

3. A semiconductive electromechanical transducer according to claim 1 in which the transistor has on said body a stage having the protrusions thereon, the base region being extended on an area including an external surface of the stage.

4. A semiconductive electromechanical transducer according to claim 1 in which the applicator is alloyed on the protrusions of the transistor by metal melted at suitable low temperature which is limited not to invade character of the transistor.
